UNITED STATES PATENT OFFICE.

JOHN OSCAR NYMAN, OF CANTON, OHIO.

METAL DOOR.

1,185,705.

Specification of Letters Patent. Patented June 6, 1916.

Application filed July 8, 1915. Serial No. 38,708.

To all whom it may concern:

Be it known that I, JOHN OSCAR NYMAN, a subject of the King of Sweden, residing at Canton, in the county of Stark and State 5 of Ohio, have invented certain new and useful Improvements in Metal Doors, of which the following is a specification.

The invention relates to improvements in metal doors, and more particularly to the 10 means for holding panels or glass plates between the stiles and rails thereof; and the objects of the invention are to provide panel holding means which may be applied to a door without the use of rivets, screws or the 15 like, and which are adapted to receive and firmly hold an ornamental molding on each side of the panel, also without the aid of rivets or screws, such means being simple in construction, yet rigid and durable. These 20 objects are attained by providing a binder for the sheet metal walls of a stile or rail having hooked longitudinal edges adapted to be slid endwise into position over a pair of inwardly projecting flanges formed in 25 the inner side edge of the stile or rail while the door is assembled, said binder being provided with a channel adapted to receive and hold the panel or glass plate of the door. When it is desired to use a glass 30 plate in the door, the top rail is provided with a detachable upper edge wall, the binder being formed in two parts yoked together by a channel bar suspended from the detachable wall, so that when the glass is 35 broken, the channel bar may be withdrawn and a new glass may be inserted in the door through the rail.

For convenience in illustration, I have 40 shown a door having a steel panel in the lower portion and a glass plate in the upper portion in the accompanying drawings, wherein—

Figure 1 is a front elevation of a door 45 embodying my invention; Fig. 2, a fragmentary sectional view on line 2—2 Fig. 1; and Fig. 3, a fragmentary sectional view on line 3—3, Fig. 1.

Similar numerals refer to similar parts 50 throughout the drawings.

The door comprises the stiles 1 connected together by means of a top rail 2, bottom rail 3, and intermediate rail 4, a glass plate 5 being inserted in the upper portion of 55 the door, and a steel panel 6 in the lower portion of the door.

The stiles 1 and bottom rail 3 are preferably formed from a single sheet of metal 7, the free ends 8 and 9 being bent inward to form the inner edge wall of the stile or rail and are provided with inwardly projecting spaced flanges 10; the usual sound deadener 11 of cork or other suitable material being provided between the side walls of the stiles or rails.

A binder 12 preferably formed of a sheet 60 of cold drawn metal having its sides bent outward beyond the plane of its edges to form shoulders 13, and its longitudinal edges bent to form the hooks 14, is adapted to be slid endwise or telescoped over the 65 flanges 10 and inner edge wall to connect the flanges together, in which position the shoulders 13 lie parallel with the inner edge wall of the stile or rail formed by the ends 8 and 9 of the sheet metal plate 7. Said 70 binder is provided with a channel extending inward midway between its sides, said channel being adapted to receive the edge 75 of a panel or glass plate inserted therein.

A pair of longitudinal grooves 16 and 17 80 are provided in each side of the binder 12, the groove 16 being formed in the shoulder 13 and the groove 17 at the edge of the channel 15, said grooves being adapted to receive and hold an ornamental molding 18 85 also preferably formed of cold drawn metal, having inturned hooked edges 19 and 20 which are sprung into the grooves. The hooked edge 19 of said molding when inserted in the groove 16, serves as a wedge 90 between the shoulder of the binder and the inner side edge of the stile which are normally spaced apart for receiving the edge 95 of the molding, the entrance of which edge securely holds the binder in engagement 100 with the flanges.

The construction of the intermediate rail 4 and binders is like that of the stiles and bottom rail, except that the rail is formed from two sheet metal plates 7^a and 7^b, a binder being provided for both the top and bottom inner edge walls of the rail, as shown in Fig. 3; so that further description thereof is unnecessary.

In order to permit the insertion of a new 105 glass, in case the glass 5 is broken, or for any other reason it is desired to provide a removable panel, the top rail 2 is provided with a detachable upper edge wall 21 having 110 depending flanges 22 adapted to fit in be-

tween the side walls of the rail, said upper edge wall being held in position flush with the top of the rail by means of spring catches 23 engaging with the beaded ends 5 24 of the flanges.

The opposite ends 8^a and 9^a, of the plates 7^c and 7^d, which form the inner edge wall of the top rail, are flanged in the same manner as the free ends 8 and 9 forming the 10 inner edge walls of the stile 1, and are connected together by means of a binder, which, for the purpose of permitting the glass or panel to be passed therethrough, is formed in two sections 12^a and 12^b having hooks 15 14^a and 14^b at one longitudinal edge and in-turned parallel flanges 15^a and 15^b at the other longitudinal edge adapted to bear against the side of the glass plate 5 inserted between them, said flanges being yoked together by means of a channel bar 25 suspended from the outer edge wall 21 by means of a support 26 secured thereto and to the channel bar by means of rivets 27 or the like.

25 It will be understood that if it is desired to use steel panels in the top portion of the door as well as the bottom, the binder 12 having the channel 15 may be used in the top rail as well as in the stiles and intermediate rail.

In assembling the door, the binders 12 are driven endwise over the inwardly projecting flanges 10 of the metal plates forming the inner edge walls of the stiles and rails, and 35 with the panel 6 and glass plate 5, in position between the binders, the stiles and rails 2, 3 and 4 are united together, as by welding, in a well-known manner. The ornamental molding 18 which may be of any desired 40 shape or design, is then sprung into place in the grooves 16 and 17 in the binders by first engaging one hooked edge in its corresponding groove and then springing or forming the other hooked edge around the adjacent 45 angle of the binder into its corresponding groove. The molding is thus firmly held in position, having no tendency to spring out of alignment and draw away from the face of the panel or plate.

50 My invention is not limited to the precise construction illustrated and described, but various changes in arrangement and construction may be made without departing from the spirit and scope thereof.

55 I claim:

1. In a metal door, a hollow stile or rail having a pair of spaced flanges in its inner edge wall, and a binder on the inner edge wall engaging with said flanges for connecting them together, said binder having a channel therein between its sides for receiving the edge of a panel, a longitudinal groove at each edge of the panel channel adapted to receive and hold one edge of an 65 ornamental molding and a longitudinal

groove in each side of the binder for receiving and holding the other edge of the ornamental molding adjacent the inner edge wall.

2. In a metal door, a hollow stile or rail 70 having a pair of spaced inturned flanges in its inner edge wall, a binder having hooked edges telescoping the flanges and inner edge wall, and means inserted between the binder and inner edge wall for holding the binder 75 in engagement with the flanges, there being a channel in the binder midway between its sides for receiving the edge of a panel.

3. A metal door including a hollow stile or rail having a pair of inturned flanges in 80 its inner edge wall spaced apart, and a binder for connecting said flanges together having a channel therein midway between its sides adapted to receive the edge of a panel, the sides of said binder being bent 85 outward beyond the plane of its edges to form shoulders and then inward to form the channel, there being a longitudinal groove in each shoulder adapted to receive and hold one edge of an ornamental molding 90 inserted between the binder and inner edge wall.

4. In a metal door, a hollow stile or rail, having a pair of spaced flanges in its inner edge wall, panel holding means comprising 95 a binder having shoulders formed on each side thereof lying parallel to the inner edge wall of the stile or rail, and hooked edges engaging with said flanges, said binder having a channel between its sides for receiving the edge of a panel and a pair of grooves in each side thereof formed in said shoulders and adjacent the edges of the channel, and an ornamental molding having inturned hooked edges adapted to be sprung into 100 105 and held by the grooves, the inturned edges of the molding fitting in the grooves in the shoulders acting as a wedge to hold the parts in place.

5. In a metal door, a hollow stile or rail 110 having a pair of spaced flanges in its inner edge wall, a binder having hooked edges adapted to engage with said flanges for connecting the parts together, said binder having a channel midway between its sides 115 adapted to receive the edge of a panel and a pair of longitudinal grooves in each side thereof, and an ornamental molding having inturned hooked edges adapted to be sprung into the grooves to be held thereby.

6. In a metal door, a hollow stile or rail having a pair of spaced flanges in its inner edge wall and a binder having hooked edges telescoping the flanges and inner edge wall, said binder having a channel midway between its sides and a pair of longitudinal grooves on each side thereof, a panel the edge of which is inserted into said channel, and an ornamental molding having inturned hooked edges adapted to be held by said 120 125 130

grooves, one of said inturned hooked edges forming a wedge between the inner edge wall of the stile or rail and the binder to hold the binder in engagement with the flanges.

7. A metal door including hollow stiles and rails, having spaced flanges in the inner edge walls thereof, binders for connecting said flanges together having a channel intermediate their sides and a longitudinal groove at each edge of the channel and a longitudinal groove in each side adjacent the inner edge wall, panels adapted to be inserted into said channels between said 10 stiles and rails, and ornamental molding having inturned hooked edges adapted to be sprung into and held by said grooves.
8. A metal door including a hollow top rail having a detachable upper edge wall 20 and a pair of spaced flanges in its inner edge wall, a sectional binder having hooked edges telescoping the flanges and inner edge wall and engaging a glass plate or panel, the sections of the binder being adapted to 25 permit the plate or panel to pass between them when the upper edge wall of the rail is detached, means inserted between the binder and inner edge wall for holding the binder

in engagement with the flanges, and means for locking the parts in position. 30

9. A metal door including a hollow top rail having a detachable upper edge wall and a pair of spaced flanges in its inner edge wall, a sectional binder engaging with said flanges and a glass plate or panel, the sections of the binder being adapted to permit the plate or panel to pass between them when the upper edge wall of the rail is detached, and means for locking the parts in position, said sections each having a pair 40 of annular grooves therein adapted to receive and hold an ornamental molding.

10. A metal door including a hollow rail having a detachable upper edge wall and a pair of spaced flanges in its inner edge 45 wall, a binder formed from two sections, each having a hooked longitudinal edge engaging with one of said flanges and an in-turned flange engaging with one side of a glass plate or panel, said sections being 50 adapted to permit the plate or panel to pass between them, and a channel bar suspended from the upper edge wall of the rail for binding the inturned flanges against the plate or panel between them.

JOHN OSCAR NYMAN.
